Herman Ament, New York, N. Y.

Application January 9, 1951, Serial No. 13,720

Term of patent 7 years

(Cl. D3—19)

To all whom it may concern:

Be it known that I, Herman Ament, a citizen of the United States of America and residing at city of New York, county of New York, State of New York, have invented a new, original, and ornamental Design for Combination Seam Ripper and Thread Picker, of which the following is a specification, reference being made to the accompanying drawing forming part thereof.

Fig. 1 is a front elevational view of the combination seam ripper and thread picker, the cap therefor being shown in removed condition; and Fig. 2 is a top elevational view of the combination seam ripper and thread picker of Fig. 1.

I claim:

The ornamental design for a combination seam ripper and thread picker, substantially as shown.

HERMAN AMENT.
